UNITED STATES PATENT OFFICE

WARREN C. ELLIS, OF FLINT, MICHIGAN, ASSIGNOR TO ELLIS PRODUCTS COMPANY, OF FLINT, MICHIGAN, A CORPORATION OF MICHIGAN

PARTING STRIP

Application filed November 8, 1930. Serial No. 494,381.

The present invention relates to parting strips for windows and has for its primary object to provide, in a manner as hereinafter set forth, a device of this character embodying a novel construction whereby a weather-proof joint is provided between the upper and lower window sashes and the window frame at all times.

Another important object of the invention is to provide a parting strip of the aforementioned character embodying a novel construction whereby lateral adjustment in the window frame grooves is had at all times should the grooves become wider or narrower due to variations in the weather or from other causes, the invention further including means for manually adjusting the strip laterally in the groove.

Another important object of the invention is to provide a party strip of the character described having formed integrally thereon a sealing lip or flange for engagement with an adjacent window sash to provide a weather-proof joint between the parting strips and the sash and to frictionally engage said sash for retaining the same in adjusted position, thus obviating the necessity for using the usual counterweights for supporting the sashes in adjusted position, the sealing lip or flange being further adapted to wear a channel or seat in the window sash for assuring a weather-proof joint.

Other objects of the invention are to provide a parting strip of the character described which will be simple in construction, strong, durable, efficient and reliable in use, which will be neat and attractive in appearance and which may be manufactured and installed in position in a conventional window frame at low cost.

All of the foregoing and still further objects and advantages of the invention may become apparent from a study of the following specification, taken in connection with the accompanying drawings wherein like characters of reference designate corresponding parts throughout the several views, and wherein:—

Figure 1 is a view principally in elevation and partly in vertical section of a window

frame equipped with parting strips in accordance with this invention.

Figure 2 is a vertical sectional view through the window frame.

Figure 3 is a fragmentary detail view in perspective of the end portions of the parting strips and the expander therefor, the same being shown separated.

Figure 4 is a horizontal sectional view taken substantially on the line 4—4 of Figure 1.

Figure 5 is a horizontal sectional view taken substantially on the line 5—5 of Figure 2.

Figure 6 is a vertical sectional view through a portion of the parting strip.

Figure 7 is a fragmentary detail view in perspective showing one end portion of the movable cover or shield which is mounted on the lower window sash and is movable therewith on the parting strips.

Referring to the drawings in detail, it will be seen that the reference numeral 1 designates generally a window frame which includes the vertical side members 2, the sill 3 and the upper cross member 4. Upper and lower window sashes 5 and 6, respectively are mounted for vertical sliding movement in the frame 1 and guide strips 7 are mounted on the frame and engageable with the outer sides of the sashes 5 and 6 in the usual manner. The inner sides of the vertical members 2 and the upper cross member 4 of the frame 1 are, as usual, provided with the grooves 8 which communicate with each other. The grooves 8 are, of course, disposed between the vertical planes of the upper and lower window sashes 5 and 6.

Mounted in the grooves 8 of the window frame 1 are the parting strips constituting this invention, the upper and lower sections 9 and 10 being mounted in the vertical side members 2 of the window frame and the sections 11 being mounted in the upper cross member 4 of the window frame. As best seen in Figure 2 of the drawings, the upper and lower sections 9 and 10 are disposed reversely with respect to each other for operative engagement with the upper and low-

er window sashes 5 and 6 in a manner which will be presently set forth.

As all of the sections are identical in construction a detailed description of one will suffice for all.

The parting strip comprises a strip of resilient metal which is bent upon itself longitudinally in a manner to provide the side walls 12 and 13 which are connected integrally with each other at their outer longitudinal edges by a connecting wall 14, which, in turn, is bent to provide a substantially U-shaped channel 15 having a side wall 16 which is spaced from the side wall 12 of the 10 parting strip and further having a side wall 16 disposed closely adjacent the side wall 13 of the parting strip. The outer portions of the walls 13 and 17 of the parting strip are curved laterally in a manner to provide a 20 sealing lip or flange 18 for frictional engagement with the adjacent side of a window sash. After continued use the sealing lip or flange 18 will wear a groove or seat 19 in the window sash and in this manner a weather- 25 proof joint is provided. When the window sash is placed in the frame the walls 13 and 17 and the sealing lip or flange 18 are sprung toward the wall 16 of the channel 15 and in this manner the sealing lip or flange 18 is 30 caused to exert a continuous pressure against the window sash.

The free longitudinal edges of the walls 12 and 13 of the parting strip are provided with integral inturned flanges 20 with which 35 is engageable a resilient expander which is designated generally by the reference numeral 22, (see Figure 3) and which is disposed longitudinally between the walls 12 and 13. The expander 22 comprises a longitudinally extending arcuate intermediate portion 23 and the flat longitudinal marginal portions 24 which are adapted for engagement on the inner sides of the flanges 20. The bottom or inner walls of the channel 16 40 and the expander 22 are provided at longitudinally spaced points with aligned openings for the passage of anchoring screws 25 having an enlargement 26 upon which the slotted heads 27 are formed. The openings 50 in the bottom wall of the channel 15 are of sufficient diameter to receive the enlargements 26 on the screws 25. Mounted on each of the anchoring screws 25 is a washer or the like 28 which is adapted to be forced against 55 the intermediate arcuate portion 23 of the expander 22 by the shoulder provided by the enlargement 26. As will be apparent, when the arcuate intermediate portion 23 of the expander 22 is forced toward the inner or 60 bottom wall of the groove 8 of the window frame 1 the flat marginal portions will be forced away from each other and in this manner the parting strip is expanded laterally in the groove 8 to provide a weather-proof joint. 65 This action takes place just before the head

27 of the screw 25 engages the inner or bottom wall of the channel 15 of the parting strip.

Mounted vertically on the side portions of the lower sash 6 is a cover or shield 29 having formed integrally thereon a right angularly disposed flange 30 which is apertured for the passage of suitable securing elements for mounting the cover or shield in position on the window sash 6. An integral flange 31 extends in an opposite direction from the free longitudinal edge of the cover or shield 29 for engagement with the free side of the parting strip sections.

As will be seen, the construction and arrangement of the parting strip is such that when the groove 8 of the window frame expands or contracts laterally, said expansion and contraction will be compensated for through the medium of the resilient expander 22 which is maintained under tension at all times and will move the walls 12 and 13 of the parting strip outwardly should the groove 8 expand laterally and which will permit the walls 12 and 13 to be moved toward each other should the groove 8 contract laterally. In addition to providing a weather-proof joint, the sealing lip or flange 18 frictionally engages the adjacent sash and supports said sash in adjusted position without the use of the usual counterweights or the like.

It is believed that the many advantages of a parting strip constructed in accordance with this invention will be readily understood, and although the preferred embodiment of the invention is as illustrated and described, it is to be understood that changes in the details of construction may be had which will fall within the scope of the invention as claimed.

What is claimed is:—

1. A parting strip of the character described comprising an elongated strip of resilient metal bent longitudinally in a manner to provide a pair of spaced, opposed side walls, the free longitudinal marginal portions of the side walls adapted for insertion in a groove in a window frame, integral in-turned flanges on the free longitudinal edges of the side walls, and means disposed between the side walls and engageable with said side walls and the flanges for yieldingly urging the side walls away from each other and against the side walls of the groove in the window frame.

2. A parting strip of the character described comprising an elongated strip of resilient metal bent longitudinally in a manner to provide a pair of spaced, opposed side walls, the free longitudinal marginal portions of the side walls adapted for insertion in a groove in a window frame, integral in-turned flanges on the free longitudinal edges of the side walls, and means disposed be-

5 between the side walls and engageable with said side walls and the flanges for yieldingly urging the side walls away from each other and against the side walls of the groove in the window frame, said means comprising an elongated metallic expander having a resilient longitudinally extending intermediate portion of substantially arcuate cross section and further having flat longitudinal 10 marginal portions engageable on the flanges of the side walls.

6. A parting strip of the character described comprising an elongated strip of resilient metal bent longitudinally in a manner to provide a pair of spaced, opposed side walls, the free longitudinal marginal portions of the side walls adapted for insertion in a groove in a window frame, integral in-turned flanges on the free longitudinal edges 15 of the side walls, and means disposed between the side walls and engageable with said side walls and the flanges for yieldingly urging the side walls away from each other and against the side walls of the groove in the window frame, said means comprising an elongated metallic expander having a resilient longitudinally extending intermediate portion of substantially arcuate cross section and further having flat longitudinal 20 marginal portions engageable on the flanges of the side walls, anchoring screws for securing the parting strip positively in the groove, and means on the anchoring screws and engageable with the expanded for actuating said expander.

7. A parting strip of the character described for mounting in a groove in a window frame comprising a pair of resilient, metallic side walls, an integral connecting wall extending between one of the longitudinal edges of the side walls, the free longitudinal marginal portions of the side walls disposed in the groove, integral in-turned flanges on the free longitudinal edges of the side walls, a resilient expander disposed between the side walls and engaged on the flanges, said expander and the connecting wall being provided with aligned openings at longitudinally spaced points, headed anchoring screws extending through the aligned openings for positively anchoring the parting strip in the groove, and a washer mounted on each of the screws, for actuation thereby and operatively engageable with the expander for actuating said expander to move the side walls away from each other and against the side walls of the groove of the window frame.

8. A parting strip of the character described comprising a pair of resilient side walls, said side walls disposed in spaced, opposed relation to each other, an integral connecting wall extending between one of the longitudinal edges of the side walls, the free 60 longitudinal marginal portions of the side

walls adapted for disposition in a groove in a window frame, the connecting wall being formed in a manner to provide a channel having one side wall disposed closely adjacent one of the first named side walls, said first named side walls and the channel side wall having their connected marginal portions curved laterally in a manner to provide a sealing lip for frictional engagement with a window sash.

9. A parting strip of the character described comprising a pair of resilient side walls, said side walls disposed in spaced, opposed relation to each other, an integral connecting wall extending between one of the longitudinal edges of the side walls, the free longitudinal marginal portions of the side walls adapted for disposition in a groove in a window frame, the connecting wall being formed in a manner to provide a channel having one side wall disposed closely adjacent one of the first named side walls, said first named side walls and the channel side wall having their connected marginal portions curved laterally in a manner to provide a sealing lip for frictional engagement with a window sash, integral in-turned flanges on the free longitudinal edges of the first named side walls, an elongated, resilient, metallic expander disposed between the first named side walls and operatively engaged therewith and with the in-turned flanges, said expander and the inner wall of the channel being provided with aligned openings at longitudinally spaced points, anchoring screws extending through the aligned openings for securing the parting strip in position in the groove.

10. A parting strip of the character described comprising a pair of resilient side walls, said side walls disposed in spaced, opposed relation to each other, an integral connecting wall extending between one of the longitudinal edges of the side walls, the free longitudinal marginal portions of the side walls adapted for disposition in a groove in a window frame, the connecting wall being formed in a manner to provide a channel having one side wall disposed closely adjacent one of the first named side walls, said first named side walls and the channel side wall having their connected marginal portions curved laterally in a manner to provide a sealing lip for frictional engagement with a window sash, integral in-turned flanges on the free longitudinal edges of the first named side walls, an elongated, resilient, metallic expander disposed between the first named side walls and operatively engaged therewith and with the in-turned flanges, said expander and the inner wall of the channel being provided with aligned openings at longitudinally spaced points, anchoring screws extending through the aligned openings for securing the parting strip in position in the groove,

said screws being provided with enlargements adjacent their headed ends, and washers mounted on the screws and engageable by the enlargements for urging the washers against the expander in a manner to actuate said expander and yieldingly urge the first named side walls outwardly against the side walls of the groove.

In testimony whereof I affix my signature.

WARREN C. ELLIS.
